UNITED STATES PATENT OFFICE

94,754

DESIGN FOR A SHOE

Nicholas J. Grossman, Lynn, Mass., assignor to Lown Shoe Company, Auburn, Maine, a cor-portion of Maine

Application January 9, 1935, Serial No. 54,778

Term of patent 3½ years

To all whom it may concern:

Be it known that I, Nicholas J. Grossman, a citizen of the United States, residing at Lynn, in the county of Essex and State of Massachusetts, have invented a new, original, and ornamental Design for a Shoe, of which the following is a specification, reference being had to the accompanying drawing, forming a part thereof, in which

The figure is a view in perspective of a shoe showing my design, the outline of the heel being conventional and shown in dot and dash lines.

The opposite side of the shoe presents substantially the same appearance as the side shown except that the buckle does not appear.

I claim:

The ornamental design for a shoe, substantially as shown and described.

In testimony whereof, I have affixed my signature hereto.

NICHOLAS J. GROSSMAN.
